DESIGN FOR A CIGARETTE BOX AND ASH TRAY UNIT

Will C. McCartney, Cambridge, Ohio

Application May 18, 1945, Serial No. 119,606

Term of patent 14 years

(Cl. D85—2)

To all whom it may concern:

Be it known that I, Will C. McCartney, a citizen of the United States of America and resident of Cambridge, county of Guernsey, and State of Ohio, have invented a new, original, and ornamental Design for a Cigarette Box and Ash Tray Unit, of which the following is a specification, reference being had to the accompanying drawing, forming part thereof, in which—

Figure 4 is a top plan view of the cigarette box with the nested ash trays depicted in Figs. 1, 2 and 3 removed, and

I claim:

The ornamental design for a cigarette box and ash tray unit, substantially as shown.

WILL C. McCARTNEY.
